CLAIM

The ornamental design for a cytometer, as shown and described.

DESCRIPTION

FIG. 1 is a perspective view of the cytometer showing our new design;

FIG. 2 is a front elevation of the cytometer of FIG. 1;

FIG. 3 is a rear elevation of the cytometer of FIG. 1;

FIG. 4 is a right-side elevation of the cytometer of FIG. 1;

FIG. 5 is a left-side elevation of the cytometer of FIG. 1;

FIG. 6 is a top plan view of the cytometer of FIG. 1; and,

FIG. 7 is a bottom plan view of the cytometer of FIG. 1.

The broken lines are included for the purpose of illustrating portions of the cytometer that form no part of the claimed design.
